Seymour W. Bonsall, Inventor

By his Attorney, *Hamackay*

UNITED STATES PATENT OFFICE.

SEYMOUR W. BONSALL, OF NEW YORK, N. Y.

TRUNK-FASTENER.

No. 888,061.

Specification of Letters Patent.

Patented May 19, 1908.

Application filed March 30, 1907. Serial No. 365,480.

To all whom it may concern:

Be it known that I, SEYMOUR W. BONSALL, a citizen of the United States, residing in the borough of Manhattan, city and State of New York, have invented a certain new and useful Improvement in Trunk-Fasteners, of which the following is a specification.

My present invention relates to an improved means for securing the entire closing edge of a trunk or packing case by operation of a single lock.

The principal object of the invention is the provision of means whereby the solidity and security of the meeting edges of a closed trunk or box may be assured and whereby it may be made impossible to pry up the cover on one corner or side when the trunk is locked. This is accomplished by use of my invention by means which do not involve any danger of accidentally catching or tearing any clothing, dresses, etc., which the trunk may contain.

The invention is illustrated in a preferred form in the accompanying drawings, wherein

Figure 1 is a perspective view of a steamer trunk provided with my improved locking devices. Fig. 2 is a sectional view of one of the side hooks and of its chamber. Fig. 3 is a top view of one of said chambers. Fig. 4 is a front view of the same.

In Fig. 1 is shown a trunk body 1 having the usual cover 2, hasp 3 and side dowels 4. These latter have the novel construction hereinafter described and are received, when the trunk closes, by the escutcheon plates 5 on the outside of the trunk body.

The lock may be of any well known construction, being fixed to and carried upon the hasp 3, secured to a strong interior shaft 6, which is pivoted in bearings 7 arranged close to the inside of the front edge of the cover 2, as shown. The shaft 6 carries 2 hooks 8 of substantially the form shown, and these hooks are firmly fixed to said shaft, 45 so as to swing when the shaft is turned by movement of the hasp 3.

Instead of the usual dowel chamber formed by a hollowed escutcheon on each side of the lock, as commonly used hitherto in trunks, I

employ a double chamber, formed of two 50 oppositely placed escutcheon plates 5 and 9, preferably united by rivets 10. A slot 11 affords communication between the inner and outer sections of the chamber formed by the two escutcheon plates.

The dowel 4 which fits into the exterior escutcheon plate 5 is hollowed out, and, when the hasp 3 is raised for opening the trunk, each hook 8 passes through its appropriate slot 11 and occupies the hollow within the 60 dowel 4 and outer chamber section. When the hasp is pressed inward, for locking the trunk (see dotted lines, Fig. 2) the shaft 6 turns both hooks 8 inward and they then occupy the hollows in the two inner escutcheon 65 plates 9, while at the same time engaging an aperture 12 in each of said plates, thus securely fastening down the edge of the cover 2 on each side of the lock.

I prefer to shape the hooks 8 so that there 70 will be no sharp point within the trunk which might catch accidentally on any clothing therein.

It is immaterial to this invention whether the hasp and hooks are placed upon the cover 75 or on the body of the trunk.

What I claim is:—

1. A case having a slotted edge, a catch arranged to swing through said slot, a hollow escutcheon plate outside of said slot, a hollowed tenon fitting said escutcheon plate and means within the case for engaging with said catch, substantially as described.

2. A case having a slotted edge, a pivoted shaft parallel to and just within the opposite 85 meeting edge, a lock-hasp fixed to said shaft, hollow escutcheon plates on opposite sides of said slot, a hollowed tenon fixed to the edge carrying said shaft and fitting the escutcheon plate outside of said slot, and a catch fixed to 90 said shaft and arranged to swing through said slot and to engage with the escutcheon plate inside of said slot, substantially as described.

SEYMOUR W. BONSALL.
